UNITED STATES PATENT OFFICE.

CONRAD DORN, OF TRAUTENFURT, NEAR SPALT, GERMANY.

LIFTING MECHANISM FOR STAMPERS IN STAMPING MILLS.

Application filed August 23, 1926, Serial No. 130,897, and in Germany July 28, 1925.

This invention relates to a mechanism for lifting the stampers of stamping mills and bronze stamping machines and it has for its object to obtain greater efficiency at the same consumption of power as in mechanisms of known type and to simplify the mechanism. A further object of the invention is to reduce the loss of stamping material in the form of dust.

10 With these objects in view lifting disks are arranged above the stampers, which have each a head, ribs with spiral shaped inner edge being arranged on said lifting disks which ribs grip, when the disks are rotating, 15 under the heads of the stampers lift the same and let them drop again as soon as the ends of the ribs have liberated the heads.

20 A stamping mill comprising the improved lifting device for the stampers is shown, by way of example, in the accompanying drawing in which:—

Fig. 1 shows a portion of a stamping mill in side elevation partly in section. For clearness sake only one of each series of 25 stampers is shown which are situated the one behind the other.

Fig. 2 is a vertical cross section through the stamping mill.

The material to be stamped is in the box 30 1 on which the posts 2, 2 are mounted. In these posts 2 a shaft 4 is journaled which is adapted to be driven by a belt pulley 3. The shaft 4 carries a number of disks 5 spaced at uniform distances. On each side 35 of each disk 5 a rib 6 is arranged the inner edge 7 of each rib 6 extending in the shape of a spiral beginning on the circumference of the disk at 11. At the end 12 each rib 6 is cut in radial direction. Under the shaft 40 4 stampers 8 are arranged which are guided in apertures in the top plate 13 of box 1 and in apertures of an intermediate plate 9 fixed on the posts 2. Each stamper 8 has a head 10 at its top end, said heads projecting into the plane of the ribs 6. On each side of each 45 disk 5 three stampers 8 are arranged the one at the side of the other.

If the stampers are in the lowest position the ends 11 of the ribs 6 grip under the heads 50 of the stampers, when the disks 5 are being

rotated, and owing to the spiral shape of the inner edges 7 of the ribs 5 the stampers are gradually raised until the thick end 12 has passed under said heads. At this instant the stampers are liberated and drop 55 by gravity.

Each disk serves to lift six stampers, whilst in lifting devices of known type one hub with a cam has to be provided for each stamper. It is evident that with disks 5 of 60 greater diameter more than 6 stampers could be lifted by each disk. On each side of each disk two ribs might be arranged so that the number of strokes would be doubled.

A great advantage of the invention is that 65 the interval between the box 1 and the intermediate guide plate 9, in which the lifting devices are generally located, is free so that it can be closed by walls. In this case devices for sucking off the air can be provided whereby the formation of dust is reduced. The improved lifting device is easy to manipulate and it requires less power than the commonly used lifting devices.

I claim:—

1. In a stamping mill, a receptacle for the material to be stamped, a shaft disposed above said receptacle, stampers having a range of movement wholly below the plane of the shaft, said stampers having headed upper ends, guiding means for the stampers disposed between their headed upper ends and the receptacle, said stampers being arranged in series, and a cam on the shaft for each two series of stampers, said cam comprising a disk provided on its opposite faces with spirally disposed cam ribs, located within the plane of its periphery, each rib operating to simultaneously lift a series of stampers.

2. In a stamping mill, a receptacle for the material to be stamped, a shaft arranged above the receptacle, guiding means between the receptacle and shaft, stampers movable through said guiding means and having headed upper ends, said stampers being arranged in longitudinal and transverse rows, and a cam on the shaft for each pair of transverse rows of stampers, each cam comprising a disk having spirally disposed cam

ribs upon its opposite faces lying wholly within the line of its periphery and providing internal cam surfaces for simultaneously lifting the stampers of the transverse rows alternately on each half of its orbit of rotation.

3. In a stamping mill, a row of stamps

having headed ends, and a rotary cam for engagement with the headed ends of the stampers, said cam comprising a disk having an internal cam surface to engage the heads of the stampers.

In testimony whereof I affix my signature.

CONRAD DORN.
